ABSTRACT

New automatic toilet bowl cleaner compositions that are capable of inhibiting the growth or multiplication of microbiological organisms are described herein. The bacteriostatic agent in the above compositions is 5-chloro-2-(2,4-dichlorophenoxy)phenol.

10 Claims, No Drawings

BACTERIOSTATIC TOILET BOWL CLEANER COMPOSITIONS

BACKGROUND OF THE INVENTION

1. Field of the Invention

This invention relates to novel toilet bowl cleaner compositions. These compositions possess antimicrobial properties at the extremely low dilutions which are normally encountered with a product of this nature.

2. Description of the Prior Art

Compositions which automatically dispense cleaning agents and cleaning adjuncts into toilet bowls have been in commercial use for many years. However, the inhibition of the growth or multiplication of microbiological organisms in products of the above nature has been difficult to accomplish. This difficulty is due to the fact that most antimicrobial agents are ineffective at the extreme dilutions that automatic bowl cleaners are used.

Recently, a new antimicrobial agent, namely, 5-chloro-2-(2,4-dichlorophenoxy)phenol has been disclosed in U.S. Pat. No. 3,506,720. The assignee of this patent (Ciba-Geigy) has published data (Irgasan DP-300, Publication DC-25) which indicates that the minimum inhibitory concentration of 5-chloro-2-(2,4-dichlorophenoxy)phenol required for specific microorganisms is 1ppm for *S. aureus* and *P. mirabilis* and 3ppm for *E. coli*.

SUMMARY OF THE INVENTION

In accordance with this invention it has now been found that the use of 5-chloro-2-(2,4-dichlorophenoxy)phenol as an antimicrobial with isopropanol, an alkoxylated primary fatty alcohol and/or a linear alkyl aryl sulfonate salt combined with known dyes and perfumes produces a cleaning formulation which exhibits bacteriostatic properties against *S. aureus*, *P. mirabilis* and *E. coli* at levels as low as 0.1 per million of the antimicrobial for a solid cleaning formulation and 0.2 parts per million for a liquid cleaning formulation.

DESCRIPTION OF SPECIFIC EMBODIMENTS

The novel liquid composition of this invention comprises:

Ingredient	% By Weight
Isopropanol	10-20
5-chloro-2-(2,4-dichlorophenoxy)phenol	0.5-6
Alkoxylated primary fatty alcohol	0.1-20
Linear Alkyl Aryl Sulfonate Salt	0.5-20
Sodium hydroxide	0-2
Water, Dye, Perfume	Sufficient to make up to 100%

The preferred formula for an effective liquid cleaning and bacteriostatic composition is as follows:

Ingredient	% By Weight
Isopropanol	14-16
5-chloro-2-(2,4-dichlorophenoxy)phenol	1.1-1.6
Alkoxylated primary fatty alcohol	4-17
Linear Alkyl Aryl Sulfonate Salt	0.5-10
Water, Dye, Perfume	Sufficient to make up to 100%

The novel solid composition of this invention comprises:

5	Ingredients	% By Weight
5-chloro-2-(2,4-dichlorophenoxy)phenol (97% minimum activity)	1-3	
Alkoxylated primary fatty alcohol	0.1-10	
Ethoxylated alcohol adduct	20-90	
Polyethylene glycol	0.1-10	
Sodium sulfate, Perfume, Dye	Sufficient to make up to 100%	

The preferred formula for an effective solid cleaning and bacteriostatic composition is as follows:

20	Ingredients	% By Weight
5-chloro-2-(2,4-dichlorophenoxy)phenol (97% minimum activity)	1-3	
Alkoxylated primary fatty alcohol	2-8	
Ethoxylated alcohol adduct	25-35	
Polyethylene glycol	2-8	
Sodium sulfate, Perfume, Dye	Sufficient to make up to 100%	

Examples of alkoxylated primary alcohols that are useful in this invention are those alkoxylated primary alcohols wherein the alkyl chain length is primarily C₁₂-C₁₈.

Examples of linear alkyl aryl sulfonate salts that are useful in this invention are the salts of an alkyl aryl sulfonate wherein the alkyl carbon chain length is C₁-C₁₅. The novel composition in its solid form contains an ethoxylated alcohol adduct whose primary alcohol chain length is about C₁₆-C₂₀. In addition to the cleaning and bacteriostatic properties that the novel formulations of this invention possess, they also have the ability to reduce the surface tension of water.

As will be illustrated in the following examples, the liquid compositions of this invention have the ability to exhibit bacteriostatic properties at use levels as low as 0.2 parts per million of the anti-microbial. The solid compositions exhibit bacteriostatic properties at use levels as low as 0.1 parts per million of the anti-microbial. The examples will also indicate the anti-microbial agents known in the prior art are either ineffective or are not readily or efficiently compounded or solubilized.

The following examples illustrate the above described invention. The bacteria employed as the test organisms are representative of both gram negative and gram positive bacteria. The test procedure employed is the Agar Plate Test and the Agar Cup Plate Test as described in U.S.D.A. circular No. 198, 1931. The results are reported as zones of inhibition and measured in millimeters.

EXAMPLE 1

60	Ingredient	% By Weight
Isopropanol (99%)	15.00	
5-chloro-2-(2,4-dichlorophenoxy)phenol (97% minimum activity)	1.50	
50% ethylene oxide	12.00	
10% propylene oxide > adduct of a linear alcohol whose carbon chain length is C ₁₂ -C ₁₈		
Sodium Xylene Sulfonate (40%)	2.50	
Water, Dye, Perfume	Sufficient to make up to 100%	

Average Zone of Inhibition (mm) Dilution 1:23,000

	<i>S. aureus</i>	<i>E. coli</i>	<i>P. mirabilis</i>
Agar Cup Plate Test	10	5	3
Agar Plate Test	5	2	1

A preferred alternate formulation is represented by Example 2.

EXAMPLE 2

Ingredient	% By Weight
Isopropanol (99%)	15.00
5-chloro-2-(2,4-dichlorophenoxy)phenol (97% minimum activity)	1.50
Triethanolaminododecylbenzensulfonate (40%)	15.00
Water, Dye, Perfume	Sufficient to make up to 100%

Average Zone of Inhibition (mm) Dilution 1:23,000

	<i>S. aureus</i>	<i>E. coli</i>	<i>P. mirabilis</i>
Agar Cup Plate Test	7	3	3
Agar Plate Test	6	3	3

EXAMPLE 3

Ingredient	% By Weight
Isopropanol (99%)	15.00
5-chloro-2-(2,4-dichlorophenoxy)phenol (97% minimum activity)	1.50
Triethanolaminododecylbenzensulfonate (40%)	11.25
50% ethylene oxide adduct	4.50
10% propylene oxide > adduct of a linear alcohol whose carbon chain length is C ₁₂ -C ₁₅	
Water, Dye, Perfume	Sufficient to make up to 100%

Average Zone of Inhibition (mm) Dilution 1:23,000

	<i>S. aureus</i>	<i>E. coli</i>	<i>P. mirabilis</i>
Agar Cup Plate Test	7	15	2.5

EXAMPLE 4

Ingredient	% By Weight
Isopropanol (99%)	4.50
n-Alkyl (60% C ₁₄ , 30% C ₁₆ , 5% C ₁₂ and 8% C ₁₈) Dimethyl Benzyl Ammonium Chloride	5.00
n-Alkyl (68% C ₁₂ , 32% C ₁₄) Dimethyl Ethylbenzyl Ammonium Chloride	5.00
50% ethylene oxide > adduct	4.00
10% propylene oxide	

-Continued

Ingredient	% By Weight
10% propylene oxide of a linear alcohol whose carbon chain length is C ₁₂ -C ₁₅ Water, Dye, Perfume	Sufficient to make up to 100%

10 Average Zone of Inhibition (mm) Dilution 1:23,000

	<i>S. aureus</i>	<i>E. coli</i>
15 Agar Cup Plate Test	2.5	0

The above is an example of the use of another antimicrobial agent employed at a much higher level than those in the previous examples which was ineffective against *E. coli*.

EXAMPLE 5

Ingredient	% By Weight
4',5 Dibromosalicylanilide and 3,4',5, Tribromosalicylanilide (1:1 mixture)	6.00
Polyethylene Glycol (molecular weight about 200)	50.00
Octyl phenoxy poly (ethyleneoxy) Ethanol	30.00
Water	Sufficient to make up to 100%

35 Average Zone of Inhibition (mm) Dilution 1:20,000

	<i>S. aureus</i>	<i>E. coli</i>
40 Agar Cup Plate Test	16	11

The above is an example of the use of a different antimicrobial agent which requires high levels of solubilizers and which was used at higher levels itself to achieve bacteriological activity.

EXAMPLE 6

Ingredient	% By Weight
3,4',5 Tribromosalicylanilide	6.00
Polyethylene Glycol (molecular weight about 200)	60.00
Octyl phenoxy poly (ethyleneoxy) ethanol	30.00
Water	4.00

Average Zone of Inhibition (mm) Dilution 1:20,000

	<i>S. aureus</i>	<i>E. coli</i>
55 Agar Cup Plate Test	10	4 (Partial)

60 This example illustrates another antimicrobial agent which requires high levels of solubilizers and which results in only a partial zone of inhibition at the high level employed.

EXAMPLE 7

Ingredient	% By Weight
Alkyl pyridinium 5-chloro-2-mercaptopbenzothiazole (96%)	12.00
N-methyl-2-pyrrolidone	60.00
Octyl phenoxy poly (ethyleneoxy) ethanol	10.00
Water	18.00

Average Zone of Inhibition (mm) Dilution 1:20,000

	<i>S. aureus</i>	<i>E. coli</i>
Agar Cup Plate Test	7	0

This example illustrates yet another antimicrobial agent which though used at a higher level does not result in a zone of inhibition on *E. coli*

EXAMPLE 8

This example illustrates the use of the solid formulation of this invention as a toilet bowl cleaner. The use dilution for microbiological activity with this composition is 0.30 parts per million of the formulation per 23,000 parts of water.

Component	% By Weight
100 moles of ethylene oxide adduct of a primary alcohol whose carbon length is C ₁₆ -C ₂₀	31.00
Polyethylene Glycol (molecular weight about 6,000)	5.00
50% ethylene oxide > adduct	5.00
10% propylene oxide of a linear alcohol whose carbon chain length is C ₁₂ -C ₁₅	
5-chloro-2-(2,4-dichlorophenoxy)phenol (97% minimum activity)	1.25
Sodium Sulfate	55.25
Perfume, Dye	Sufficient to make up to 100%

Average Zone of Inhibition (mm)

	<i>S. aureus</i>	<i>E. coli</i>	<i>P. mirabilis</i>
Agar Cup Plate Test	4.5	2	2.5

EXAMPLE 9

This Example illustrates the use of 5-chloro-2-(2,4-dichlorophenoxy)phenol in the following liquid formulation where it is present at 0.50% by weight in a use dilution of 1:23,000 and 1:40,000.

Ingredients	% By Weight
Isopropanol (99%)	15.00
5-chloro-2-(2,4-dichlorophenoxy)phenol (97% minimum activity)	0.50
50% ethylene oxide > adduct	12.00
10% propylene oxide of a linear alcohol whose carbon chain length is C ₁₂ -C ₁₅	
Water	67.75
Sodium Xylene Sulfonate (40%)	2.50

-Continued

Ingredients	% By Weight
Dye	1.00
Perfume	1.25

Average Zone of Inhibition (mm)

	<i>S. aureus</i>	<i>E. coli</i>	<i>P. mirabilis</i>
Agar Cup Plate Test (Dilution 1:23,000)	6	2.5	2
Agar Cup Plate Test (Dilution 1:40,000)	4	1.5	0

EXAMPLE 10

Component	% By Weight
Ethoxylated Alcohol Adduct	31.00
Polyethylene Glycol (mol wt. about 6000)	5.00
Oxyethylated Alcohol Surfactant	5.00
4',5 Dibromosalicylanilide, 3,4'	
Tribromosalicylanilide (1:1 mixture)	2.50
Sodium Sulfate	54.00
Perfume, Dye	Sufficient to make up to 100%

Average Zone of Inhibition (mm)

	<i>S. aureus</i>	<i>E. coli</i>	<i>P. mirabilis</i>
Agar Cup Plate Test	2.5	0	0

This example illustrates the use of an antimicrobial agent which does not exhibit activity in the composition.

Component	% By Weight
Ethoxylated Alcohol Adduct	31.00
Polyethylene Glycol (mol. wt. about 6000)	5.00
Oxyethylated Alcohol Surfactant	5.00
3,4',5 Tribromosalicylanilide	2.50
Sodium Sulfate	54.00
Perfume, Dye	Sufficient to make up to 100%

Average Zone of Inhibition (mm)

	<i>S. aureus</i>	<i>E. coli</i>	<i>P. mirabilis</i>
Agar Cup Plate Test	0	0	0

This example illustrates a total lack of activity of an antimicrobial in the composition.

The following data represents the ability of the preferred compositions of this invention to help retard stain buildup on a ceramic surface immersed in a solution containing an iron salt. Results are reported as

units of stain pickup on white ceramic tiles. Less than 1 unit difference is visible to the naked eye.

	Average Units Iron Stain Pickup	Surface Tension Dynes/cm
Composition (Example 1)	4.1	41.4
Water	5.8	72
Composition (Example 8)	2.5	33
Water	6.1	72

We claim:

1. A method for preventing the growth or multiplication of *E. Coli* in toilet bowls which comprises dispensing into the water of a toilet an antibacterial liquid composition consisting essentially of:

Ingredient	% By Weight
Isopropanol	10-20
5-chloro-2-(2,4-dichlorophenoxy)phenol	0.5-6
Alkoxylated primary fatty alcohol	0.1-20
Linear alkyl aryl sulfonate salt	0.5-20
Sodium hydroxide	0-2
Water, dye, perfume	Sufficient to make up to 100%

wherein 5-chloro-2-(2,4-dichlorophenoxy)phenol is present at a use dilution level in amounts of about 0.2 parts per million to less than 3.0 parts per million and wherein the alkyl chain length of the alkoxylated primary alcohol is from about 12 carbon atoms to about 18 carbon atoms.

2. An antibacterial liquid composition consisting essentially of:

Ingredient	% By Weight
Isopropanol	14-16
5-chloro-2-(2,4-dichlorophenoxy)phenol	0.5-1.6
Alkoxylated primary fatty alcohol	4-17
Linear alkyl aryl sulfonate salt	0.5-10.0
Sodium hydroxide	0-2
Water, dye, perfume	Sufficient to make up to 100%

wherein 5-chloro-2-(2,4-dichlorophenoxy)phenol is present at a use dilution level in amounts of about 0.2 parts per million to less than 0.7 parts per million and wherein the alkyl chain length of the alkoxylated primary alcohol is from about 12 carbon atoms to about 18 carbon atoms.

3. A composition according to claim 2, wherein the linear alkyl aryl sulfonate salts have alkyl carbon chain length from C₁-C₁₅.

4. A composition according to claim 2 wherein the alkoxylated primary fatty alcohol is a 50% ethylene oxide, 10% propylene oxide adduct of a linear alcohol whose carbon chain length is C₁₂-C₁₅.

5. A composition according to claim 3 wherein the alkyl aryl sulfonate salt is sodium xylene sulfonate.

6. A composition according to claim 3 wherein the alkyl aryl sulfonate salt is tri-ethanolaminododecylbenzenesulfonate.

7. A method for preventing the growth or multiplication of *S. Aureus*, *P. Mirabilis* and *E. Coli* in toilet bowls which comprises dispensing the composition of claim 2 into the water of a toilet to prevent such growth.

8. A composition according to claim 2 wherein 5-chloro-2-(2,4-dichlorophenoxy)phenol has a lower limit of about 1.1 percent.

9. An antibacterial liquid composition consisting essentially of:

Ingredient	% By Weight
Isopropanol	14-16
5-chloro-2-(2,4-dichlorophenoxy)phenol	0.5-1.6
Alkoxylated primary fatty alcohol	4-17
Sodium hydroxide	0-2
Water, dye, perfume	Sufficient to make up to 100%

wherein 5-chloro-2-(2,4-dichlorophenoxy)phenol is present at a use dilution level in amounts of about 0.2 parts per million to less than 0.7 parts per million and wherein the alkyl chain length of the alkoxylated primary alcohol is from about 12 carbon atoms to about 18 carbon atoms.

10. An antibacterial liquid composition consisting essentially of:

Ingredient	% By Weight
Isopropanol	14-16
5-chloro-2-(2,4-dichlorophenoxy)phenol	0.5-1.6
Linear alkyl aryl sulfonate salt	0.5-10.0
Sodium hydroxide	0-2
Water, dye, perfume	Sufficient to make up to 100%

wherein 5-chloro-2-(2,4-dichlorophenoxy)phenol is present at a use dilution level in amounts of about 0.2 parts per million to less than 0.7 parts per million.
